US0D1083950S

(12) **United States Design Patent** (10) **Patent No.:** **US D1,083,950 S**
Yao (45) **Date of Patent:** **** Jul. 15, 2025**

(54) **DISPLAY SCREEN OR PORTION THEREOF
WITH GRAPHICAL USER INTERFACE**

(71) Applicant: **HUAWEI TECHNOLOGIES CO., LTD.**, Guangdong (CN)

(72) Inventor: **Liying Yao**, Shanghai (CN)

(73) Assignee: **HUAWEI TECHNOLOGIES CO., LTD.**, Shenzhen (CN)

(**) Term: **15 Years**

(21) Appl. No.: **29/812,976**

(22) Filed: **Oct. 26, 2021**

(30) **Foreign Application Priority Data**

Apr. 27, 2021 (CN) 202130247717.7

Primary Examiner — Jack Reickel

(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing my new design;

FIG. 2 is a front view of a second embodiment of a display screen or portion thereof with graphical user interface showing my new design; and,

FIG. 3 is a front view of a third embodiment of a display screen or portion thereof with graphical user interface showing my new design.

The dash-dot broken lines in the drawings illustrate the display screen or portion thereof and form no part of the claimed design. The dash-dash broken lines in the drawings illustrate portions of the graphical user interface that form no part of the claimed design.

1 Claim, 3 Drawing Sheets
